UNITED STATES PATENT OFFICE.

CHARLES H. BRIGDEN, OF WALTHAM, MASSACHUSETTS.

CLOCK ESCAPEMENT.

Application filed September 3, 1921. Serial No. 498,222.

To all whom it may concern:

Be it known that I, CHARLES H. BRIGDEN, a citizen of the United States, residing at Waltham, in the county of Middlesex and 5 State of Massachusetts, have invented new and useful Improvements in Clock Escapements, of which the following is a specification.

This invention relates to clock escapements more particularly designed for time-pieces in which extreme accuracy is desired. 10 In such escapements it is desirable to eliminate all parts subjected to friction, since friction is a factor subject to wide fluctuations from time to time due to varying lubrication and surface conditions of the contacting parts.

This invention provides a construction wherein the usual crutch and pallet bearings are entirely eliminated so that friction 20 is greatly reduced and in its preferred forms requires no lubrication between the pallet and the escape teeth.

Further this invention provides a mechanism 25 in which separate means for locking the escape wheel is unnecessary, eliminating the complications produced by the presence of such parts and the friction inherent therein.

It is also important that the force acting 30 on the pendulum to trip the pallet and to permit rotation of the escape wheel shall be uniform. While weights for driving the entire movement may be mounted so as to 35 exert a substantially uniform force for this purpose, it is not always convenient or possible to employ them and the force of the volute springs commonly used varies considerably depending on the extent of 40 winding and on frictional engagement between successive convolutions.

This invention provides a mechanism by 45 which a variable propelling power such as a spring may be caused to exert a substantially constant force to actuate the pendulum by interposing a leaf spring therebetween, this spring being flexed by the propelling power to a substantially constant extent at each actuation and exerting its force directly 50 against the pendulum. This leaf spring also furnishes the pivotal axis of the pallet so that no friction bearings therefor are required.

Further this invention provides a construction 55 adaptable to a solid or divided pallet and with most of its desirable char-

acteristics to pin wheel escapements and in connection with anchor pallets.

For a more complete understanding of this invention, together with further objects and advantageous details and combinations of parts, reference may be had to the accompanying drawings in which,

Figure 1 is a front elevation of one form of escapement, the pendulum being shown 65 in mid position.

Figure 2 is a side elevation of the same.

Figure 3 is a view similar to Figure 1, but showing the pendulum swung to one side, the position of the parts being somewhat 70 exaggerated for clearer showing.

Figure 4 is a perspective of the pallet.

Figures 5, 6, and 7 are front elevations of modified constructions.

Figure 8 is an elevation showing an application 75 of the invention to a pin wheel escapement.

Figure 9 is a side elevation of the same.

Figure 10 is a perspective of one form 80 of pallet suitable for pin wheel escapements.

Figure 11 is a perspective of an anchor pallet.

Figure 12 is a fragmentary detail showing the relations of escape teeth to the pallet points in the construction shown in Figure 85 11.

Referring more particularly to Figures 1 to 4 at A is shown a supporting plate for the clock movement through which passes a shaft 1 forming part of the gear 90 train driven by a motor of any suitable description and which has fixed at its outer end an escape wheel 2. As shown this escape wheel has five teeth 3 thereon. This is the minimum number which can be used 95 satisfactorily, but any higher odd number may be substituted.

Above the wheel 1 is fixed a block 4, forked at its lower extremity to receive between the forked portions and to be clamped 100 therein the upper end of a leaf spring 5. A screw 6 may be used to clamp this spring in position. Somewhat below the screw 6 is fixed the upper end of a pendulum hanger 7, the space between the top of the hanger and the block 4 providing a section of unsupported spring furnishing a hinge joint for the pendulum. The lower end of the member 7 has fixed thereto a block 8 carrying a pin 9 transversely thereof over which may be engaged a bifurcated hook 10 fixed to the upper end of the pen-

dulum rod 11, the pendulum weight being indicated at 12.

Beneath the block 7 the spring 5 is attached to the upper end of a pallet 13, the portion of the spring between the pallet and the block 7 providing an axis about which the pallet may oscillate. The lower end of this pallet is provided with an opening 14 and projecting part way across this opening 10 at the top and bottom are the pallet points or stones 15 and 16. These stones are positioned so as to be engaged alternately by teeth of the escape wheel above and below the shaft 1. Above the opening 14 the pallet 15 is provided with oppositely extending arms 17 and 18 and fixed in position to be engaged at certain times by these arms are a pair of banking studs or stops 19 and 20. These parts are so proportioned that when 20 one of the points or stones 15 and 16 is engaged by an escapement tooth 3, rotation of the escape wheel due to the clock motor urges the pallet laterally to bring one of the arms 17 or 18 into engagement with its banking stud, the spring 5 flexing for this purpose. The flexing of this spring imparts a force tending to swing the pendulum in the same direction as the pallet has been moved, the pallet being carried therewith. Sufficient swing of the pendulum in response to this force flexes the spring 30 in the opposite direction and moves the pallet about the banking stud so as to disengage the pallet point from the escapement tooth which 30 thereupon escapes therefrom. The tooth on the opposite side of the axis of the shaft 1 thereupon engages the opposite pallet point throwing the pallet to its extreme lateral position in contact with the other banking 35 stud. This action flexes the spring 5 in the opposite direction and imparts a thrust tending to swing the pendulum in the same direction. This pallet point remains in contact with the escapement tooth until the 40 pendulum has swung nearly to its extreme position in this direction, (its inertia causing a further motion after the change in direction of the force exerted by the spring) whereupon it is removed from the path of the tooth which is then free to move until the wheel is stopped by engagement of a tooth with the first pallet point whereupon the cycle of operations is repeated.

It will thus be seen that the force applied 55 to swing the pendulum is exerted through the leaf spring 5 which is flexed the same amount at each actuation and therefore exerts a uniform force tending to swing the pendulum at each actuation varying power 60 of the driving motor merely changing the pressure exerted against the banking studs. It is also seen that the spring furnishes a pivotal connection for the pallet which has no other bearings except against the banking 65 stud or stops. The pallet thus has a

bodily movement between the banking studs pivoting about its suspension axis or center in the spring 5, and it also rocks about the banking studs in turn as the pendulum swings until the escapement wheel is released and drives the pallet against the other stud.

In Figure 5 a modified construction is shown in which the pendulum is hung from the lower end of a yoke 27, this yoke being supported by a leaf spring 28 from a block 29 within the yoke and made fast to the frame plate A. Projecting from the upper end of the yoke 27 is a second leaf spring 30 to the upper end of which is fixed the lower 70 end of the pallet 31. This pallet 31 has a pair of points or stones 32 herein shown as formed of circular pins flattened on the side facing the escape wheel 33. The upper end of this pallet is formed as an arm 34 which projects between a pair of banking studs 35 and 36. The action of this mechanism is substantially the same as that previously described, the escape wheel 33 acting alternately against the points 32 and bringing 75 the arm 34 alternately against the studs 35 and 36. This action flexes the spring 30 alternately in opposite directions to impart swinging motion to the pendulum, this swinging motion acting through the spring 80 30 to move the pallet sufficiently to disengage the points 32 alternately from the escape wheel. In this case, however, the pendulum is supported from below the pallet 85 instead of above as in the other form.

In Figure 6 is shown a further modification in which the pendulum is hung at a point above the pallet substantially as shown in Figures 1 to 4, the pendulum rod being here indicated at 37 fixed to a leaf spring 38 90 made fast at 39 and having fixed at its lower end beneath the attachment to the pendulum, the upper end of the pallet 40. This pallet is provided with points or studs 41 and the lower end thereof is prolonged to form an arm 42 which vibrates between the stops or banking studs 43 and 44, the action of this arm being identical with that in the form 95 shown in Figure 5.

In Figure 7 is shown a further modification in which the pendulum 50 is supported at the lower end of a spring 51 fixed at its upper end at 52, the pendulum extending above the point 52 and carrying the lower end of a spring 53. The upper end of spring 53 is attached at 54 to a pallet 55 having points or studs 56 thereon engageable by the teeth of the escape wheel 57. Extending laterally of the pallet 55 are a pair of stop arms 58 and 59 which may impinge against banking studs 60 and 61. As herein shown each banking stud has passed therethrough an abutment screw as 62 and 63 and adjacent the inner end thereof is a fixed member 64 and 65. With this form of 100

the device, swinging of the pendulum to release the pallet stones causes considerable movement of the abutment arms 58 and 59 against the banking studs. By adjustment 5 of the screws 62 and 63 resistance to this motion may be varied at opposite ends of the traverse of the pallet and by proper adjustment the pendulum may be regulated asymmetrically, that is, so that it may swing at 10 equal distances in either direction.

In Figures 8, 9, and 10 is shown another form of device particularly designed for pin wheel escapements. In this case the pendulum is shown at 70, the upper end thereof 15 being made fast to a leaf spring 71 fixed at its upper end at 72 to part of the clock frame, the spring 71 projecting below the attachment of the pendulum thereto and being made fast to the upper end of the pallet 20 73. This pallet 73 has an opening 74 therethrough, and projecting from opposite directions partly across this opening are the points or stones 75 and 76. A pin escape wheel is shown at 77 fixed to a shaft or arbor 78. This wheel has pins 79 extending from one face thereof which are engageable by the points 75 and 76. In this form the points or stones 75 and 76 have inclined upper faces 80 and 81 on which the pins 79 impinge, these faces being inclined in opposite directions so as to urge the pallet alternately in opposite directions. This form of the 25 device requires lubrication since there is rubbing contact between the faces 80 and 81 and it is also necessary to employ rest nibs or 30 stops 82 and 83 at the ends of the points against which the pins 79 rest before the points are moved to disengage them by means of the swinging of the pendulum. 35 While these stop lugs or nibs may be sufficient in themselves to insure against release of the pins except by the motion of the pendulum, it might also be desirable to employ fixed banking studs or abutments 84 and 40 85 contacted alternately by arms 86 and 87 projecting laterally from the pallet as in the other forms herein shown.

While in this form the pendulum is shown as pivoted above the pivot of the pallet, it 45 is quite evident that constructions similar to those in Figures 5 and 7 might be employed wherein the pivotal point of the pendulum is below that of the pallet.

In Figures 11 and 12 is shown another 50 form of the invention as applied to anchor pallets. In this form the pallet 90 is supported at the end of a leaf spring 91 which may be attached to the pendulum in the manner of any of the devices above described, herein shown this being of the type 55 wherein this connection is above the connection of the pallet. In this form inclined faces 92 and 93 are provided on the pallet points for engagement with the escapement 60 teeth as is usual with anchor pallets, and for

insuring against premature release of the teeth, rest nibs 92' and 93' and arms 94 and 95 contacting with banking studs 96 and 97 have been indicated. The action of this device is substantially the same as in the pin 70 wheel escapement, the teeth of the escapement wheel riding on the inclined faces 92 and 93 and urging the pallet alternately in opposite directions whereby the spring 91 is flexed and vibrating impulses transmitted to 75 the pendulum by the motion of which the engagement between the pallet points and the escape teeth is successively released.

While the various forms of the invention 80 above described afford mechanisms which are extremely accurate in operation it will be noted that they also eliminate many of the parts usually found necessary in escapement mechanisms whereby the cost of the mechanisms may be considerably reduced. 85

Having thus described certain embodiments of this invention it should be evident to those skilled in the art that many modifications and changes might be made without departing from the spirit or scope of the invention as defined by the appended claims. 90

I claim:

1. A mechanism of the class described comprising an escape wheel, a pallet cooperating with said wheel, a pendulum for actuating said pallet, and a spring carrying said pallet and actuating said pendulum. 95

2. A mechanism of the class described comprising an escape wheel, a pallet cooperating with said wheel, a leaf spring 100 supporting said pallet, and a pendulum deriving substantial swinging impulses from said spring and actuating said pallet to successively release teeth of said escape wheel.

3. A mechanism of the class described 105 comprising an escape wheel, a pallet cooperating with said wheel, a leaf spring carrying said pallet and forming a pivotal center therefor, fixed banking elements against which said pallet contacts alternately by pressure of said escape wheel, flexing said spring alternately in opposite directions, and a pendulum actuated by the flexing of said spring to swing and move the pallet to successively release teeth of said 110 escape wheel. 115

4. A mechanism of the class described comprising an escape wheel, a pendulum, and a rockable and bodily movable pallet, the bodily movement of said pallet imparting swinging impulses to said pendulum, and said pendulum acting by its swinging to rock said pallet to successively release teeth of said escape wheel. 120

5. A mechanism of the class described 125 comprising an escape wheel, a pendulum, and a pallet cooperating with said escape wheel and pivotally carried by said pendulum.

6. A mechanism of the class described 130

- comprising an escape wheel, a pendulum, and a pallet cooperating with said escape wheel and pivotally carried by said pendulum and bodily movable therewith.
- 5 7. A mechanism of the class described comprising an escape wheel, a pendulum, a pallet cooperating with said escape wheel and mounted on said pendulum, and stops for limiting the movement of said pallet.
- 10 8. A mechanism of the class described comprising an escape wheel, a pendulum, a pallet cooperating with said escape wheel and mounted on said pendulum, stops for limiting the movement of said pallet and 15 over which said pallet moves, and means for independently adjusting the resistance to relative motion between said pallet and each stop.
9. A mechanism of the class described 20 comprising an escape wheel, a pendulum, and a pallet cooperating with said escape wheel carried and actuated by said pendulum to successively release teeth of said escape wheel.
- 25 10. A mechanism of the class described comprising an escape wheel, a pendulum, and a pallet spring-supported from said pendulum and cooperating with said escape wheel.
- 30 11. A mechanism of the class described comprising an escape wheel, a pendulum, a pallet spring-supported from said pendulum to move therewith and to rock relative thereto, and fixed banking elements against which 35 said pallet is rocked alternately by pressure from teeth of said escape wheel, whereby said spring is flexed to impart swinging impulses to said pendulum and the movement of said pallet effected by the swinging of 40 said pendulum acts to successively release teeth of said escape wheel.
12. A mechanism of the class described comprising an escape wheel, a pendulum, a pallet, a leaf spring connecting one end of 45 said pallet with said pendulum and providing a center of oscillation therefor outside the center of oscillation of said pendulum, and a pair of fixed banking elements positioned at either side of said pallet to limit 50 its oscillation.
13. A mechanism of the class described comprising an escape wheel, a pendulum, a pallet cooperating with said wheel, and a flexible spring for imparting substantial 55 swinging impulses to said pendulum and also serving as a pallet axis.
14. A mechanism of the class described comprising an escape wheel, a pendulum, a pallet cooperating with said wheel and carried by and movable relative to said pendulum, and stops to limit the movement of 60 said pallet to prevent release of said escape wheel until said pendulum has substantially completed its swing in either direction.
15. A mechanism of the class described comprising an escape wheel, a pallet having faces for alternate engagement with teeth of said wheel and actuated to successively release said teeth, and a rest nib on each face to prevent premature release of said teeth. 70
16. A mechanism of the class described comprising an escape wheel, a pendulum, a spring forming an axis for said pendulum, a pallet cooperating with said wheel, a spring forming an axis for said pallet and through which swinging impulses are imparted to said pendulum, and means to limit the swing of said pallet acting to prevent release of said wheel before the substantial completion of swinging in either direction of said pendulum. 75
17. In a clock having a motor, an escape wheel driven by said motor, a pallet cooperating with said wheel, means for controlling said pallet, and means by which impulses of uniform force are imparted to said controlling means regardless of fluctuations in the force of said motor. 80
18. A mechanism of the class described, comprising an escape wheel, a pallet cooperating with said wheel, a pendulum, means independent of said pallet for pivotally supporting said pendulum, and a spring interposed between said pallet and pendulum, said spring being tensioned by movement of said pallet by said escape wheel to swing said pendulum and being tensioned by the swinging of said pendulum to move said pallet to release said escape wheel. 85
19. A mechanism of the class described, comprising an escape wheel, a pallet cooperating with said wheel, a pendulum, means independent of said pallet for pivotally supporting said pendulum, and a spring alternately tensioned by movements of said pallet and pendulum to impart movement to said pendulum and pallet respectively to cause periodic release of said escape wheel. 90
20. A mechanism of the class described, comprising an escape wheel, a pallet cooperating with said escape wheel, means for controlling said pallet to alternately release and stop said escape wheel, and a spring tensioned to a uniform extent regardless of fluctuations in force applied to said escape wheel for actuating said controlling means. 95
21. In a mechanism of the class described, an escape wheel, a pallet cooperating with said escape wheel and having a pair of inclined faces engageable alternately by teeth of said wheel and by which engagement swinging impulses are imparted to said pallet, a rest nib at one side of each inclined face to stop the pallet tooth riding on the corresponding face, and a pendulum deriving swinging impulses from the swinging impulses of said pallet acting to move said pallet further to move said rest nibs out of engagement with said teeth. 100
- 110
- 115
- 120
- 125
- 130

22. In a mechanism of the class described, an escape wheel, a pallet cooperating with said escape wheel and having a pair of inclined faces engageable alternately by teeth 5 of said wheel and by which engagement swinging impulses are imparted to said pallet, a rest nib at one side of each inclined face to stop the pallet tooth riding on the corresponding face, a spring tensioned by 10 the swinging of said pallet, and a pendulum actuated by said spring and acting at the latter portion of its swing in each direction to reversely tension said spring to rock said pallet and release a rest nib, thereby permitting 15 an escape tooth to engage the opposite pallet face and further reversely ten-
- sion said spring to impart swinging impulse in the opposite direction to said pendulum.
23. A mechanism of the class described comprising a pendulum, an escape wheel, 20 and a pallet cooperating with said wheel and pendulum and rockable about a plurality of centers, the rocking of said pallet about one of said centers acting to impart a swinging impulse to said pendulum, and the 25 rocking of said pallet about another center acting to release said pallet from said escape wheel.

In testimony whereof I have affixed my signature.

CHARLES H. BRIGDEN.
